UNITED STATES PATENT OFFICE.

WILLIAM GRAY, OF HARTFORD, CONNECTICUT, ASSIGNOR TO THE GRAY AUTOMATIC TELEPHONE PAY STATION COMPANY, OF SAME PLACE.

DESIGN FOR A TELEPHONE TOLL-BOX.

SPECIFICATION forming part of Design No. 25,128, dated February 4, 1896.

Application filed November 7, 1895. Serial No. 568,232. Term of patent 7 years.

To all whom it may concern:

Be it known that I, WILLIAM GRAY, a citizen of the United States, and a resident of Hartford, in the county of Hartford and State of Connecticut, have invented a new Design of Telephone Toll-Boxes; and I do hereby declare the following, when taken in connection with the accompanying drawings, and the letters of reference marked thereon, to be a full, clear, and exact description of the same, and which said drawings constitute a part of his specification.

Referring to the drawings, Figure 1 represents a front view of a telephone toll-box embodying my design. Fig. 2 is a detail view in central vertical section of the box.

This invention relates to a design for a toll-box used in connection with a set of telephone-instruments; and the design consists in the configuration and ornamentation as described and shown in the accompanying illustrations.

The main portion A of the box is semicircular, and in that regard, as well as in outline, it corresponds to a half-section of a bell, a projection B from the lower rounded part C of the bottom resembling in outline the hammer or tongue of a bell. The surface of

the box is ornamented with transverse bands D, and on the top there is a ribbon-scroll E, flowing from a central projection, G, on top of 30 the bell and curving outward on opposite sides in the swallow-tails H, as shown in the accompanying illustrations.

The main semicircular-shaped portion of the box forms a cover or receptacle which is 35 attached to a flat base-piece, that is designed to be secured to the back board of a telephone or like device, and a chamber I is formed in the main portion A of the box, the thickness of the toll-box or width of chamber therein 40 being practically equal to one-half the diameter of the bell represented in plan view in the drawings.

I claim—

The design for a telephone toll-box, substantially as described and shown in the accompanying illustrations.

In testimony whereof I have signed this specification in the presence of two subscribing witnesses.

WILLIAM GRAY.
